UNITED STATES PATENT OFFICE.

JOHN VAN CAMP, OF LONG BEACH, CALIFORNIA, ASSIGNOR OF ONE-HALF TO JOHN E. OWEN, OF VENICE, CALIFORNIA.

AMUSEMENT DEVICE.

1,339,871.

Specification of Letters Patent. Patented May 11, 1920.

Application filed April 21, 1919. Serial No. 291,731.

To all whom it may concern:

Be it known that I, JOHN VAN CAMP, a citizen of the United States, residing at Long Beach, in the county of Los Angeles and State of California, have invented new and useful Improvements in Amusement Devices, of which the following is a specification.

My object is to make a live amusement device, and my invention consists of the novel features herein shown, described and claimed.

Figure 1 is a perspective of a live amusement device embodying the principles of my invention, and taken from the front end, as indicated by the arrow 1 in Fig. 2.

Fig. 2 is a vertical longitudinal sectional detail on the line 2—2 in Fig. 1.

Fig. 3 is a top plan view in the direction indicated by the arrow 3 in Fig. 2, parts being broken away and shown in section.

Fig. 4 is an enlarged fragmentary sectional detail on the same plane as Fig. 2.

Fig. 5 is a diagram of the lighting system.

The floor 1 is rectangular in plan and a woven wire fence 2 extends upwardly from the back end of the floor, woven wire fences 3 and 4 extend upwardly from the sides of the floor, and a woven wire fence 5 extends upwardly from the front end of the floor. A trough 6 is mounted upon the upper edge of the fence 5 across the front end of the device, and balls 7 are placed in this trough for the use of the customers.

A tunnel 8 is formed to extend a considerable distance longitudinally both ways from the center of the floor 1. A wall 9 is mounted transversely across the rear end of the floor 1, the lower edge of the wall being some distance above the floor to form the space 10. A secondary floor 11 is connected to the lower edge of the vertical wall 9 and extends forwardly and downwardly and joins the floor 1 at the forward end of the tunnel 8. A platform 12 extends forwardly from the upper part of the wall 9, a wall 13 extends upwardly in line with the wall 9 from the rear side of the platform 12, partitions 14, 15, 16 and 17 extend forwardly from the wall 13 upon the platform 12 to form pigpens 17', 18, 19 and 20, and the central chamber 21. A cover 22 is mounted upon the wall 13 and the partitions 14, 15, 16 and 17 and ends 23 and 24 are inserted.

A partition 25 is mounted parallel with the wall 9 and some distance in front, and a platform 26 extends forwardly from the partition 25 on a level with the platform 12. Doors 27, 28, 29 and 30 are formed for the pigpens 17', 18, 19 and 20, said doors leading from the pigpens on to the platform 26.

A chute 31 is mounted at a steep incline and extends from some distance above the forward edge of the platform 26 downwardly and forwardly to the front end of the tunnel 8, and a ladder 32 leads upwardly from the platform 26 to the upper end of the chute 31, and a mattress 33 is mounted upon the floor 1 in front of the lower end of the chute 31.

Springs 34 are connected to the doors 27, 28, 29 and 30, so that when the doors are released the springs will pull the doors open. A catch 35 is applied to each door so that when the doors are swung closed the latches will catch and hold the doors against the tensions of the springs. A cord 36 is connected to the doors 27, 28, 29 and 30 and extends around to the front end of the device so that the operator may pull the cord and close the doors.

Brackets 37 are mounted behind the lower edge of the partition 35, there being a bracket for each pigpen. An actuator 38 is pivotally connected to each bracket, each of said actuators being a board hanging downwardly and swinging freely above the rear end of the secondary floor 11. A crank arm 39 is connected to each actuator and an elastic link 40 connects each crank arm to the corresponding catch 35 so that when the actuator 38 swings backwardly the catch 35 is drawn and the corresponding door released to swing open. A curtain 41 is suspended from the forward edge of the platform 26 downwardly in front of the actuators 38, there being an opening 42 through the curtain in a horizontal line with the center of each actuator 38, so that if a customer takes a ball 7 and throws it through one of the openings 42 it will strike the corresponding actuator 38 and release the corresponding door 27, 28, 29 or 30.

Circuit breakers 43, 44, 45 and 46 are constructed in connection with the hinges of the doors 27, 28, 29 and 30, so that when the doors are closed the circuits are broken, and when the doors are opened the circuits are closed. The main line wires 47 and 48 are

properly located and the wire 48 is connected to the stationary side of each circuit breaker 43, 44, 45 and 46. The wire 47 is connected through the lamps 49, 50, 51 and 52 to the movable sides of the circuit breakers so that when the doors are opened the lamps are illuminated. In a like manner the line 47 is connected through the lamps 53, 54, 55 and 56. The lamps 49, 50, 51 and 10 52 are mounted in the pigpens 17, 18, 19 and 20, and the lamps 53, 54, 55 and 56 are mounted on top of the pigpens. The line 47 is connected through the bell 57 to each of the movable sides of the circuit breakers 43, 15 44, 45 and 46, so that when any door opens the bell will ring.

A flock of live pigs 58 is placed in the space 59 below the secondary floor 11 and in front of the rear fence 2, and this space 20 59 becomes the pigs' home. The pigs are, of course, more or less trained and when the amusement device is in operation an attendant takes a pig from the home 59 and places the pig in one of the pens 17', 18, 19 or 20, 25 and then another pig in another pen, and so on until each pen has a pig. Doors 60 are formed in the wall 13 at the back of the pig pens so that the attendant may open the door 60 and place the pig in the pen. The 30 pens are normally dark and the pig is restless and homesick. A customer takes a certain number of balls 7 and throws the balls at the openings 42 and every time a ball passes through an opening 42 and strikes 35 an actuator 38 the corresponding door 27, 28, 29 or 30 will be released and swung open, thereby illuminating the lamp within the pigpen, and the corresponding lamp on top of the pigpen and the sudden illumination 40 of the lamp will scare the pig more or less and the pig will rush out of the door and up the ladder 32 and slide down the chute 31 and turn a somersault from the chute and land upon the mattress 33, straighten 45 himself up and make a rush for home, and the only avenue from the mattress space to the pig's home 59 is through the tunnel 8.

The balls thrown at the curtain 42 will fall upon the secondary floor 11 and roll 50 toward the forward end of the floor 1. Side boards 61 and 62 are mounted above the fences 3 and 4 to keep the balls from going over the fences. A back board 63 is mounted across the rear end above the pigpens to prevent the balls from flying over the pigpens, and the names of the pigs may be 55 shown upon the board 63 above the corresponding pens, and above these names is an illustration of the operation of the device.

Various changes may be made without departing from the spirit of my invention as 60 claimed.

I claim:

1. An amusement device comprising an inclosure having a forward end, and a rear

end and having a bottom floor, an inclined way extending from near the rear end of the inclosure forwardly and downwardly toward the bottom floor, a tunnel connecting the forward end of the inclosure through the inclined way with the rear end of the inclosure, means forming pens above the inclined way for inclosing acting animals, said pens having self opening doors and latches for holding the doors closed, a platform in front of the doors adapted to form a walk for the animals, a chute leading from the platform forwardly and downwardly upon which the animals may act, a curtain suspended from the platform and having openings and actuating devices behind the curtains for operating the latches to release the doors thereby 80 releasing the acting animals.

2. An amusement device adapted to be operated in connection with a plurality of live pigs, an inclosure forming a home for the pigs, means forming a tunnel leading to the pigs' home, pigpens mounted above the pigs' home, a chute in communication with the pigpens and extending downwardly and forwardly to the front end of the tunnel, 85 self-opening doors for the pigpens, lamps in the pigpens and adapted to be illuminated by opening the doors, a curtain extending downwardly in front of the pigpens and having openings, actuators mounted behind the openings and connections between the 90 actuators and the doors, whereby a ball striking the actuator will release a door and allow the door to swing open and turn on the light and allow a pig in the pen to escape from the pen and slide down the chute 95 and return to his home through the tunnel.

3. In an amusement device, an inclosure, a home for a plurality of animals, a pen separate from said home, an entrance door to said pen through which animals are placed into the pen, an exit door in said pen leading to said inclosure, a target, and means actuated by said target for releasing said exit door to allow the animal to escape from the pen into said inclosure when the target is hit, and a conduit leading from 105 said inclosure into said home.

4. In an amusement device, an inclosure, a home for a plurality of animals, a pen separate from said home, an entrance door to 110 said pen through which animals are placed into the pen, an exit door in said pen leading to said inclosure, a lamp in said pen, said lamp extinguished when said exit door is closed, a target, and means actuated by 115 said target when hit for releasing said exit door and lighting said lamp, whereby the animal is caused to rush out of said pen into said inclosure, and a conduit leading from said inclosure into said home.

In testimony whereof I have signed my name to this specification.

JOHN VAN CAMP.
